TAPE EMBOSsing TOOL OR SIMILAR ARTICLE

Henry Ruskin, Cranford, N.J., assignor to Swingline Inc.,
Long Island City, N.Y., a corporation of New York

Filed Oct. 23, 1968, Ser. No. 14,121

Term of patent 14 years

Int. Cl. D18—99

U.S. Cl. D64—10

FIG. 1

FIG. 2

FIG. 3

FIG. 4

FIG. 5

FIG. 6

FIG. 7

FIG. 1 is a top perspective view of a tape embossing tool or similar article showing my new design.

FIG. 2 is a top plan view thereof.

FIG. 3 is a side elevational view thereof.

FIG. 4 is a bottom plan view thereof.

FIG. 5 is a front elevational view thereof.

FIG. 6 is a rear elevational view thereof.

FIG. 7 is a side elevational view thereof similar to that of FIG. 2 but showing the embossing lever in extended position.

I claim:

The ornamental design for a tape embossing tool or similar article, as shown.
